UNITED STATES PATENT OFFICE.

ISAAC I. TATOM, OF WEST POINT, GEORGIA.

IMPROVEMENT IN INSULATORS FOR TELEGRAPH-LINES.

Specification forming part of Letters Patent No. **139,436**, dated May 27, 1873; application filed December 7, 1872.

To all whom it may concern:

Be it known that I, ISAAC I. TATOM, of West Point, in the county of Troup and State of Georgia, have invented a new and valuable Improvement in Telegraph-Insulators; and I do hereby declare that the following is a full, clear, and exact description of the construction and operation of the same, reference being had to the annexed drawings making a part of this specification, and to the letters and figures of reference marked thereon.

Figure 1 of the drawings is a vertical longitudinal section of my insulator. Fig. 2 is a transverse section of same.

This invention has relation to telegraph-insulators; and it consists in the novel construction and arrangement of the parts constituting an insulator, as hereinafter described and claimed.

A in the drawings represents the glass insulator or spool, made in two semi-cylindrical sections, and having a central aperture through which the wire *a* passes. B designates the peg or frame to which the insulator is applied. Said frame or peg has a threaded shank, D, to be used in attaching it to a telegraph-pole or other object. The upper part of the peg is constructed with a tenon or offset, *a'*, to the shoulder *b* of which is hinged the block *c*. The parts *a' c* are correspondingly recessed to pro-

vide a cylindrical cavity for the reception of the insulator, which is therein retained by the end flanges *d*. A shouldered latch, *e*, which is hinged to the upper end of the block or cover *c*, fits a mortise or slot cut in the top of the part *a'*, and serves thus to retain the parts *a' c* together.

The insulator, it will be seen, may be easily inserted in or removed from its socket when desired.

Sometimes I construct the peg without the flanges *d*, but use an insulator or spool having end flanges, which flanges prevent end play.

Having fully described my invention, what I claim as new and desire to secure by Letters Patent, is—

The insulator having the frame B provided at its lower end with the threaded shank D, and its upper end having the offset *a'* and shoulder *b*, hinged block *c*, with the shouldered latch *e*, all constructed and operating in the manner shown and described.

In testimony that I claim the above I have hereunto subscribed my name in the presence of two witnesses.

I. I. TATOM.
